UNITED STATES PATENT OFFICE

2,233,800

FLUID SYSTEM

Lyman F. Whitney, Cambridge, Mass., assignor,
by mesne assignments, to Stator Corporation, a
corporation of Rhode Island

Application October 14, 1937, Serial No. 168,957

7 Claims. (Cl. 62—115)

This invention relates to heat exchange systems, and more particularly to refrigerating systems of the type which receive their energy from a source of heat and have relatively low pressures, so that pressure differences may be balanced by liquid columns.

The present invention provides safety means which becomes automatically operable to absorb heat when an excessive amount of heat is supplied to the boiler of the refrigerating system or the like. This arrangement, for example, may be employed in a refrigerating system of the general character disclosed in United States Patent No. 1,761,551 to Eastman A. Weaver, wherein mercury is vaporized to provide a stream of propellant vapor which pumps refrigerant vapor from a cooler to a condenser, the boiler pressure being balanced by a column of the condensed propellant, e. g., mercury. Under some practical operating conditions the heater of such a system may be improperly adjusted so that it would tend to cause abnormal operation of the system and possible denuding of the boiler. When the boiler of such a system receives an abnormally high quantity of heat, the pressure balancing mercury column tends to increase in height, and eventually the mercury might overflow from the top of this column and the boiler would be denuded at the high temperature then prevailing.

In accordance with this invention, a spill-over arrangement may be provided to receive liquid from the top of the pressure-balancing column when the column reaches a predetermined height, and an auxiliary or safety boiler receives the propellant which has thus spilled over. This auxiliary boiler is in heat transfer relation to the main boiler, so that when the former contains a body of liquid, it tends to reduce the temperature of the main boiler. A heat dissipator is provided to condense vapor supplied by the auxiliary boiler and to return the condensed vapor to the main propellant circuit.

A further aspect of the invention relates to the provision of trap means containing a liquid body to balance pressure differences, and arranged so that the liquid body may be automatically replenished under all operating conditions.

In the accompanying drawing, the figure is a diagrammatic view of a refrigerating system constructed in accordance with the present invention.

A system of the character to which the present invention is directed may be provided with a heater 1, such as a gas burner, which supplies energy to the system. This burner, for example,

may cause the vaporization of a propellant liquid, such as mercury, in a boiler 2, the propellant vapor passing upwardly through the riser pipe 3 to an aspirator nozzle 4. The propellant vapor issues from the nozzle 4 at high velocity into a mixing chamber 5, the latter being connected by a duct 6 to a cooler 7, which normally contains a body of liquid refrigerant, such as water or a solution of an anti-freeze agent in water. The vapor stream issuing from the nozzle 4 draws vapor through the pipe 6, thus causing evaporation of the liquid in the cooler 7. The mixed vapors pass into the funnel 8, where the refrigerant vapor is compressed and propellant is condensed. The funnel 8 is provided with cooling means, such as fins 10, to aid the condensation of the propellant. The compressed refrigerant passes from the funnel through the duct 12 to the refrigerant condenser 14, while condensed propellant is received from the funnel by a drain 15. This drain comprises one leg of a trap 16, the opposite leg of which communicates with an entraining chamber 20 of a purger 21 of the type more fully disclosed in my copending application Serial No. 167,402, filed October 5, 1937.

The refrigerant condenser 14 may be of any desired form and may be provided with any suitable cooling means, such as the fins 22. The condenser may also be provided with a gas-collecting drum 23, this drum preferably being arranged below the portion of the condenser which is provided with the cooling means. This drum receives the condensed refrigerant and the non-condensable gases which appear in the system. A purger supply tube 25 receives the gases from the drum 23 and supplies them to the entraining chamber 20 of the purger. The latter is provided with a capillary drop tube 23 in which successive globules of the propellant liquid entrain bodies of the non-condensable gas, compressing the same as they move downwardly in the tube. The gas and propellant flowing out of the lower end of the tube is received by a body 24 of liquid propellant in a vat 25, the upper surface of this propellant body being exposed to the atmosphere so that the gas or air may bubble upwardly through the liquid body and be exhausted to the atmosphere.

A deflector 26 of the type disclosed in the copending application of Raymond W. Tibbets, Serial No. 168,958, filed October 14, 1937, is arranged at the lower end of the drop tube 23 so that the gases emitted from the tube cannot rise into the return duct 30, but so that propellant may rise in the same and may spill over into the

duct 35. If desired, a very small vent (not shown) may be arranged between chamber 20 and duct 30, as disclosed in my application Serial No. 167,402, to permit pressure equalization in these parts of the system. The duct 35 is connected to a trap 36, the opposite leg of which communicates with a boiler return pipe 37. The upper end of the pipe 37 communicates with the lower part of mixing chamber 5, so that propellant particles which condense in this part of the system may drain back to the lower part of pipe 37. Under normal operating conditions the pipe 37 contains a column of propellant which balances the boiler pressure.

15 The condensed refrigerant which is received by the drum 23 passes into a drain which is connected to a trap 41 containing a body of the heavy propellant. As the refrigerant piles up in the drain it provides a liquid head sufficient 20 to cause some of the refrigerant to bubble through the trap 41 and thence pass through the duct 44 back to the cooler 1, it being evident that the propellant in trap 41 balances the difference in pressure between the cooler and the 25 condenser.

In accordance with this invention, a secondary or safety boiler 50 may be provided in heat-transfer relation to the heater 1 and boiler 2. The boiler 50, for example, may comprise a metal 30 dome welded to the upper part of the boiler 2. A duct 53 extends upwardly from the secondary boiler 50 and has a spill-over connection through duct 54 with the return pipe 31, the duct 54 preferably inclining downwardly toward the return pipe. The duct 53 is continued upwardly beyond its connection with the pipe 54, and its upper end communicates with a heat dissipator 55, which may be in the form of a duct section provided with a plurality of cooling fins. This 35 duct section inclines downwardly from its connection with the duct 53 and communicates with a duct 57 connected to the lower part of trap 36.

A duct 60 communicates with the upper end of duct 57 and is provided with a trap 61 connected 40 to the bottom of the cooler, so that condensed propellant particles passing into the cooler may be received by the trap 61 and may spill over from the latter into the duct 60, thus being received by the duct 57 and the trap 36.

50 The arrangement of duct 57 so that it supplies mercury to the lower part of trap 36 is particularly advantageous under certain operating conditions, since it permits the pressure-balancing body of mercury constantly to be replenished and 55 maintained in the trap. The pipe 60 inclines downwardly from its connection to the upper part of duct 57 and has a connection with the upper part of the return pipe 31, this connection permitting substantial equalization of pressures 60 above the legs of trap 61.

The safety boiler 50 normally is empty and the pressure-balancing column in pipe 37 may stand, for example, at substantially the level shown in the accompanying drawing. However, 65 should the burner 1 be improperly adjusted so that too much gas is being supplied to the same, the boiler pressure rises and the height of the liquid column in pipe 37 rises correspondingly until it reaches the spill-over connection 54, 70 whereupon the mercury from the top of the column spills over through the pipes 54 and 53 to the secondary boiler 50.

Since under such conditions the boiler 50 is at a relatively high temperature the mercury 75 which is received thereby is vaporized, thus ab-

sorbing some of the heat from the heater 1 and tending to reduce the temperature of the boiler 2. The resulting mercury vapor passes upwardly through the duct 53 to the dissipator 55 where it is condensed. The resulting condensate drains into the duct 51, being received by the trap 36 and directed by the latter to the return duct 37. Some of the vapor from the secondary boiler 50 may be received by the spill-over pipe 54, condensing in this pipe and draining directly back to the return duct 37. It is evident that the secondary or safety boiler 50 provides means automatically operable to absorb part of the heat from the burner 1 when an excessive quantity of heat is supplied to the boiler 2. Accordingly, the pressure in the system does not rise unduly even when the gas burner is improperly adjusted and an abnormally large quantity of heat is supplied to the boiler 2, and under such conditions sufficient mercury is kept in the boiler to prevent denuding thereof and consequent liability of injury to the system.

It is evident that the present invention affords a safety arrangement automatically operable to absorb heat from a boiler when an excessively large amount of heat is supplied to the same, and such an arrangement is particularly useful in a system such as a low pressure refrigerating system, wherein the boiler pressure is balanced by a liquid column.

It should be understood that the present disclosure is for the purpose of illustration only and that this invention includes all modifications and equivalents which fall within the scope of the appended claims.

I claim:

1. Heat exchange system comprising a main boiler, a heater to supply heat to said boiler, a secondary boiler which is normally empty, and means responsive to an increase in the pressure of the main boiler beyond a predetermined point thereupon to supply liquid to the secondary boiler, said secondary boiler then being effective in absorbing some of the heat supplied by the heater so that the pressure in the main boiler may automatically be prevented from rising further.

2. Heat exchange system comprising a main boiler, a heater to supply heat to said boiler, a secondary boiler which is normally empty, and means responsive to an increase in the pressure of the main boiler beyond a predetermined point thereupon to supply liquid to the secondary boiler, said secondary boiler then being effective in absorbing some of the heat supplied by the heater so that the pressure in the main boiler may automatically be prevented from rising further, a heat dissipator receiving vapor from the secondary boiler, condensing said vapor and directing the resulting condensate to the main boiler, whereby the secondary boiler may be denuded when the pressure in the main boiler falls below a predetermined point.

3. Heat exchange system comprising a main boiler, a heater for supplying heat to said boiler, a normally inoperative heat dissipator, and means operable in response to an undue rise in the boiler pressure to cause the dissipator to become operative in receiving some of the heat supplied by the heater and dissipating the same, whereby the boiler is protected against overheating.

4. Heat exchange system comprising a main boiler, a duct connected to the boiler and containing a column of liquid balancing the boiler pressure, a secondary boiler which is normally empty and which is in heat-transfer relation to

the heater, means receiving liquid from the top of the column when the column reaches a predetermined height in response to a rise in the pressure of the main boiler, said means supplying the liquid to the secondary boiler so that the latter absorbs some of the heat supplied by the heater, a heat dissipator receiving vapor from the secondary boiler, condensing said vapor and returning the resulting condensate to the liquid column in said duct.

5. Heat exchange system comprising a fluid circuit including a main boiler and a condenser, a secondary boiler in heat-transfer relation to the main boiler, said fluid circuit also including a 10 return duct connected to the main boiler and containing a column of liquid balancing the main boiler pressure, said secondary boiler receiving liquid which spills over from the top of said column after the column reaches a predetermined 15 height in response to a rise in the pressure of the main boiler, a heat dissipator which receives and condenses vapor from the secondary boiler, said dissipator returning the resulting condensate to the liquid column in said duct.

6. Heat exchange system comprising a fluid circuit including a main boiler, a condenser, a trap receiving condensate from the condenser, and a return duct connected to the main boiler and containing a column of liquid balancing the main 20 boiler pressure, said duct receiving condensate from the trap and returning the same to the boiler, a secondary boiler in heat transfer relation to the main boiler, said second boiler normally being empty, said secondary boiler receiving liquid which spills over from the top of said 25 column after the column reaches a predetermined 30 height in response to a rise in the pressure of the main boiler, a heat dissipator which receives and condenses vapor from the secondary boiler, said dissipator returning the resulting condensate to the liquid column in said duct.

height in response to a rise in the pressure of the main boiler, a heat dissipator which receives and condenses vapor from the secondary boiler, a duct receiving the resulting condensate from the dissipator and directing the same to the lower part of said trap whereby said last-named condensate may also be returned to the main boiler.

7. Refrigerating apparatus of the class described comprising a propellant circuit and a refrigerant circuit having a part in common where 10 propellant vapor pumps and compresses refrigerant vapor and where the propellant vapor is condensed, said propellant circuit also including a boiler, a vapor pipe connecting the boiler to said common part, and a return pipe connecting said 15 common part and the boiler, said refrigerant circuit also including a cooler and a refrigerant condenser, a receptacle in heat transfer relation to the boiler, a duct extending upwardly from said receptacle, a heat dissipator connected to 20 the upper end of said duct and to the propellant return pipe, said receptacle, duct, dissipator and return pipe being arranged so that under normal operating conditions a column of liquid propellant in the pipe balances the boiler pressure, but so 25 that, when the boiler pressure rises unduly, propellant spills over into the upwardly extending duct and receptacle, being vaporized in the latter and condensed in the dissipator, the condensed propellant draining from the dissipator back to 30 said return pipe, whereby when an unnecessarily large quantity of heat is supplied to the boiler the excess heat will be employed in vaporizing propellant in said receptacle.
